(57) **CLAIM**

The ornamental design for a travel pillow with chin-supporting structure as shown and described.

DESCRIPTION

FIG. 1 is a perspective view of the travel pillow with chin-supporting structure with the chin strap stored in a storage pocket;

FIG. 2 is a front elevation view of the travel pillow with chin-supporting structure of FIG. 1;

FIG. 3 is a rear elevation view of the travel pillow with chin-supporting structure of FIG. 1;

FIG. 4 is a right elevation view of the travel pillow with chin-supporting structure of FIG. 1;

FIG. 5 is a left elevation view of the travel pillow with chin-supporting structure of FIG. 1;

FIG. 6 is a top view of the travel pillow with chin-supporting structure of FIG. 1;

FIG. 7 is a bottom view of the travel pillow with chin-supporting structure of FIG. 1; and,

FIG. 8 is another perspective view of the travel pillow with chin-supporting structure of my design with the chin-supporting structure shown extended.

The broken lines in the figures show stitching which is part of the claimed design.
